Fig. 4.

Fig. 5.

Figure 1 is a perspective view of a portable electric saw embodying my new design, viewing the same from the top, front and one side thereof;

Figure 2 is a perspective view of the portable electric saw, viewing the same from the front, substantially at eye level;

Figure 3 is a perspective view showing the side opposite that shown in Figure 1, and viewed substantially at eye level;

Figure 4 is a plan view of the portable electric saw; and

Figure 5 is a perspective view thereof viewing the same side as that shown in Figure 1, but substantially straight on.

The dominant features of my design reside in those portions thereof shown in full lines.

I claim:

The ornamental design for a portable electric saw, as shown and described.
